Kurt H. Wittke, Berkeley, Mich., assignor to
Eureka Vacuum Cleaner Company, Detroit,
Mich., a corporation of Michigan

Application November 11, 1944, Serial No. 116,277

Term of patent 14 years

(Cl. D9—2)

To all whom it may concern:

Be it known that Kurt H. Wittke, a citizen of the United States of America and a resident of Berkeley, in the county of Oakland and State of Michigan, has invented a certain new, original, and ornamental Design for a Suction Cleaner Nozzle or Similar Article, of which the following is a specification, reference being had to the accompanying drawing, forming a part thereof, and wherein:

Fig. 1 is a side elevational view of a suction cleaner nozzle or similar article, showing my new design;

Fig. 2 is a plan view of the same; and
Figs. 3 and 4 are end elevational views of the same.

I claim:

The ornamental design for a suction cleaner nozzle or similar article, as shown.

KURT H. WITTKE.
